DESIGN FOR A SMOKER'S APPLIANCE

Edward H. Burdick, Chicago, Ill.

Application June 24, 1935, Serial No. 57,384

Term of patent 3½ years

To all whom it may concern:

Be it known that I, Edward H. Burdick, a citizen of the United States, residing at Chicago, in the county of Cook and State of Illinois, have invented a new, original, and ornamental Design for a Smoker's Appliance, of which the following is a specification, reference being had to the accompanying drawing, forming a part thereof.

In the drawing,

Fig. 1 is a perspective view of a smoker's appliance showing my new design.

Fig. 2 is a side elevation thereof;

Fig. 3 is a front view of the appliance.

I claim:

The ornamental design for a smoker's appliance, as shown.

EDWARD H. BURDICK.
